UNITED STATES PATENT OFFICE.

THOMAS J. LEWIS, OF NEW YORK, N. Y.

DESIGN FOR VANITY CASE.

Application filed October 26, 1925. Serial No. 15,261. Term of patent 14 years.

To all whom it may concern:

Be it known that I, THOMAS J. LEWIS, a citizen of the United States, residing at New York, in the county of New York and State of New York, have invented a new, original, and ornamental Design for Vanity Case, of which the following is a specification, reference being had to the accompanying drawing, forming part thereof.

In the drawing:

Fig. 1 is a plan view of a vanity case, showing my new design.

Fig. 2 is a perspective view thereof.

It is understood, of course, that the ornamentation shown on the left half in Figure 1 is carried out in like manner over the right half.

I claim:

The ornamental design for vanity case, as shown.

THOMAS J. LEWIS.
